UNITED STATES PATENT OFFICE

GORDON E. P. WRIGHT, OF FORD CITY, AND EDWARD G. MAXWELL, OF TARENTUM, PENNSYLVANIA, ASSIGNORS TO PITTSBURGH PLATE GLASS COMPANY, A CORPORATION OF PENNSYLVANIA

PACKING CRADLE

Application filed May 21, 1929. Serial No. 364,931.

The invention relates to a cradle for supporting and turning the boxes in which plate glass is packed. During the packing operation, the box must be supported with one of its large sides in approximately a horizontal plane, but before such box is lifted by the overhead crane and tackle, it must be turned so that the large sides are in substantially a vertical plane, in order to avoid the danger 10 of the box flexing sufficiently to crack the glass. The present invention is designed to provide a simple means for supporting the glass and then turning it from a horizontal to a vertical position, which can be handled 15 with ease and safety by the operator. A further object is the provision of a cradle which can be used with boxes of widely varying size. One embodiment of the invention is illustrated in the accompanying drawings, 20 wherein:

Figure 1 is a plan view of the cradle. Fig. 2 is an end elevation. Fig. 3 is a side elevation in the position occupied when the cradle is loaded. And Fig. 4 is a side elevation 25 showing the cradle in the position occupied when not loaded.

Referring to the drawings, the frame of the cradle is made up of two side pieces of wood 1 and 2 having rocker surfaces, as illustrated, 30 and suitably tied together and braced by bars of wood and iron rods. There are a number of iron rods 3, 4, 5, etc. extending between the rockers 1 and 2 provided with spacers in the form of nuts on the rods engaging the inner faces of the members 1 and 2. The wood 35 braces comprise the members 6 and 7 and the diagonal braces 8 and 9 suitably secured to the members 1 and 2. A transverse bar 10 at the rear end of the frame serves as a handle 40 for tilting the frame in transferring the loaded box from the cradle to the floor as later described.

A pair of legs 11 are provided at the rear end of the frame, and when such frame is 45 in unloaded position, as indicated in Fig. 4, the ends of the legs just clear the floor and act as stops for preventing the frame from tilting too far in that direction. When the cradle is loaded, as indicated in Fig. 3, it is 50 swung to the right and a pair of legs 12 serve

to limit the rocking movement of the cradle in that direction. These legs are pivoted upon a rod 13 and are connected together by a transverse bar 14. They may be swung from the rear end of the frame by means of 55 a bar 15 pivoted by means of a U-bolt 16 to the central portion of the bar 14. This bar has at its end a handle or grip 17 and intermediate its ends is a notch 18. When in the position illustrated in Figs. 3 and 4, the notch 60 18 is engaged by a plate 19 carried by the transverse bar 7, such bar being secured to the rocker members 1, 2. The plate 19 serves as a lock for the bar 15 so that the legs are securely held in the position shown. The edges of 65 the members 1 and 2 are sheathed with strips of sheet metal 21 in order to protect them from wear and at the end of the frame are bent up so as to form the stop members 22. The purpose of these stop members is to 70 prevent the box on the cradle from slipping off when the cradle is being tilted from the loaded position shown to discharge position with the stops 22 in contact with the floor or adjacent thereto.

When the cradle is in loading position with the box thereon, it occupies a position shown in Fig. 3 with the supporting surface 23 in a horizontal position. This surface is of sufficient length to support the smaller boxes 80 which are loaded on the cradle, such as the box A. Such box lies with its center of gravity to the right of the vertical center line of the cradle, so that when the legs 12 are swung to the rear by means of the bar 15, 85 the cradle tends to move by gravity to discharge position with the stop 22 in contact with the floor and very little effort is required on the part of the operator to control its movement from the handle 10. To the 90 rear of the supporting surface 23 is a second upwardly inclined surface 24. This surface is engaged by the ends of boxes larger than the box A, such as the box B, indicated in dotted lines. Still larger boxes, such as the 95 box C, indicated in dotted lines, may also be loaded upon the cradle. With all of such boxes, the center of gravity of the box will lie to the right of the center line of the cradle so that when the legs 12 are moved out of 100

position, the cradle will tend to swing by gravity to discharge position. The effect of providing the inclined surface 24 is to insure that the center of gravity of the box being loaded shall be higher and further to the right than would be the case if no inclined surface were used and the surface 23 were extended further to the rear to accommodate boxes of larger size. The construction, therefore, renders the cradle easier to tilt and discharge when larger size boxes than the box A are loaded. When large size boxes, such as the boxes B and C, are loaded, it is desirable to support such boxes intermediate their ends so that the bottoms thereof will remain perfectly flat under the load of glass, and in order to secure this result, a pair of tilting braces 25 are employed. Such braces are pivoted upon a transverse rod 20 and are tied together by means of a transverse bar 26. The braces are held in adjusted position by means of a pair of rack bars 27 pivoted to the braces and secured together so as to move in unison with the tie bar 28 (Fig. 1). The lower faces of these racks are adapted to engage a transverse rod 29 extending through the rocker members 1, 2. By this adjusting means, the braces 25 can be held at any desired position to engage the bottoms of boxes lying at different elevations. The braces are shown in dotted lines in Fig. 3 in the vertical position of adjustment occupied when supporting the box C, and are also shown in such figure in horizontal position.

When the device is not in service, both sets of legs 11 and 12 are out of engagement with the floor upon which the cradle rests, as indicated in Fig. 4, so that the device may be dragged around from place to place without interference by the legs. When it is desired to load a box, such as the box A, it is placed upon the surface 23 of the cradle with its ends projecting out past the rocker members 1 and 2. At this time, the cradle assumes the position indicated in Fig. 2 with the surface 23 horizontal and the legs 12 in engagement with the floor. Glass is now brought to the box and it is packed in the usual way and a cover applied, and the operator tilts the cradle by releasing the bar 15 from its catch and pulling the legs 12 to the left so that the cradle is free to tilt. This tilting is controlled by the operator, who grasps the handle 10, so that when the stop 22 reaches the floor, the box will have assumed approximately a vertical position. The cradle can now be easily disengaged from the box leaving it in this position, suitable tackle being employed for carrying the box away to storage.

What we claim is:

1. In combination in a packing cradle, a rocker frame having a flat supporting surface for a box to be loaded on its upper side extending rearward from the front end of the frame, a swinging leg pivoted to the

frame at its front end for engaging the floor on which the cradle is mounted and adapted to maintain the cradle with the supporting surface in substantially horizontal position when the cradle is loaded, and a second supporting surface on the upper side of the cradle extending upwardly and to the rear from the rear edge of the first surface.

2. In combination in a packing cradle, a rocker frame having a flat supporting surface for a box to be loaded on its upper side extending rearward from the front end of the frame, a swinging leg pivoted to the frame at its front end for engaging the floor on which the cradle is mounted and adapted to maintain the cradle with the supporting surface in substantially horizontal position when the cradle is loaded, a second supporting surface on the upper side of the cradle extending upward and to the rear from the rear edge of the first surface, and an adjustable brace carried by the frame adapted to engage and support the bottom of a box on the cradle intermediate its ends when such box is supported in part by each of said surfaces.

3. In combination in a packing cradle, a rocker frame having a flat supporting surface for a box to be loaded on its upper side extending rearward from the front end of the frame, a swinging leg pivoted to the frame at its front end for engaging the floor on which the cradle is mounted and adapted to maintain the cradle with the supporting surface in substantially horizontal position when the cradle is loaded, a second supporting surface on the upper side of the cradle extending upward and to the rear from the rear edge of the first surface, a brace pivoted to the frame and adapted to be swung so that it projects above said first surface to engage the bottom of a box which rests in part on one surface and in part on the other surface, and means for holding the brace in a plurality of different positions of adjustment.

In testimony whereof, we have hereunto subscribed our names.
